KATHERINE E. CUNNINGHAM, OF CHICAGO, ILLINOIS, ASSIGNOR TO THE H. W. GOSSARD CO., OF CHICAGO, ILLINOIS, A CORPORATION OF DELAWARE

COMBINATION GARMENT

Application filed August 29, 1930. Serial No. 478,591.

This invention relates to combination garments and has for its object to provide an improved garment of lightweight which will mold the figure throughout. A particular object of this invention is to provide a garment adapted to correctly confine and mold the busts and the abdomen with complete comfort to the wearer and to fit closely above and below the busts without exerting appreciable pressure thereon.

The above objects are accomplished, according to this invention, by a combination garment comprising a corset and brassière, said brassière including a front portion of soft inelastic material adapted to cover the body across the busts and being sewn to the upper edge of the corset, end sections of similar material adapted to be crossed at the back, shoulder straps attached to the front portion and end sections, elastic straps attached to said end sections, and means for fastening said straps to the back of the corset.

In the preferred form of the invention the end sections are broader than the adjacent ends of the front portion of the brassière and are sewn to the front portion and also down the side of the corset to a point adapted to lie below the diaphragm of the wearer, each end section having a pair of elastic straps attached thereto which terminate in a tab provided with means for fastening same to the back of the corset. The elastic straps of each pair diverge from the tab so that one of each pair is adapted to exert a pull along the lower part of its adjacent end section and across that portion of the corset adapted to cover the diaphragm and the other strap of each pair is adapted to exert a pull along the upper portion of its adjacent end section and cross the upper part of the front portion of the brassière.

Due to the above described construction the figure is perfectly controlled across the diaphragm and the abdomen and the upper part of the front portion of the brassière is held snugly against the body of the wearer above the busts while no uncomfortable pressure is exerted on the busts. The present construction confines the busts and gives them a correct uplift form.

In the accompanying drawings:

Fig. 1 is a rear view of a figure showing a combination garment embodying the invention:

Fig. 2 is a rear view of the garment shown in Fig. 1 with the brassière in flat position.

As shown in the drawings, the combination garment comprises a corset 5 of inelastic material having longitudinal side elastic portions 6 and 7, and garters 8. The corset opens at one side and is provided with hooks 9 and eyes 10 for fastening it about the wearer and has a portion 11 adapted to extend above the diaphragm of the wearer intermediate the busts. A gusset 12 is inserted at the top of the back of the corset to give added adjustment. If desired, the corset may be boned.

The brassière comprises a front portion 15 of inelastic soft material adapted to cover the body across the busts and is sewn to the upper edge of the corset. End sections 16 and 17 are sewn to the front portion 15 and down the sides of the corset at 18 and 19 to a point adapted to lie below the diaphragm and at about the waistline of the wearer. The end sections are extended rearwardly beyond the sides to overlie the back of the wearer of the garment. Each of the end sections have sewn thereto a pair of elastic straps 25 and 26 which terminate in a tab 27 provided with buttonholes 28 adapted to be fastened to buttons 29 on the back of the corset. Shoulder straps 34 and 35 are attached to the front portion 15 and to the end sections 16 and 17, respectively, of the brassière. It is preferred to use elastic material in the shoulder straps so that the garment, when worn with the garters 8 of elastic material attached to the stockings, will be kept in position yet permit freedom of movement to the wearer.

As clearly shown in Fig. 1, the end sections 16 and 17 are adapted to be crossed at the back and the elastic straps 25 and 26 of each pair diverge from their tab 27 so that the strap 26 is adapted to exert a transverse pull on the lower part of its adjacent end section and across that portion of the corset adapted to cover the diaphragm while the strap 25 is adapted to exert a pull along the upper

part of the adjacent end section and across the upper part of the front portion 15 of the brassière adapted to cover the body above the busts. The general construction and arrangement of the end sections is such that they exert a downward pull when they are fastened and placed under tension. As a result of this construction, the diaphragm of the wearer is held flat and the brassière 10 above the busts is held snugly against the body of the wearer without exerting uncomfortable pressure on the busts. Due to the elastic straps attached to the end section the brassière, without variation, will correctly fit figures whose bust girths differ considerably.

The end sections of the brassière being crossed at the back and fastened to the corset tend to exert an upward pull on the front 20 of the brassière thereby giving the desired uplift form to the figure.

The invention claimed is:

1. A combination garment comprising a corset and a brassière, said brassière comprising a front portion adapted to cover the body across the busts and being attached to the upper edge of the corset, end sections adapted to be crossed at the back and terminating in pairs of elastic straps, and means for fastening said straps to the back of the corset, said straps in each pair diverging from the point adapted to be fastened to the corset so that one strap of each pair is adapted to exert a pull along the lower edge of its adjacent end section and the other strap of each pair is adapted to exert a pull along the upper edge of its adjacent end section.

2. A combination garment comprising a corset having elastic garters and a brassière, 40 said brassière comprising a front portion of soft inelastic material adapted to cover the body across the busts and being sewn to the upper edge of the corset, end sections adapted to be crossed at the back and terminating in pairs of elastic straps, shoulder straps of elastic material attached to the front portion and the end sections, and means for fastening said straps to the back of the corset, the first said straps in each pair diverging from 45 the point adapted to be fastened to the corset so that one strap of each pair is adapted to exert a pull along the lower edge of its adjacent end section and the other strap of each pair is adapted to exert a pull along the upper edge of its adjacent end section.

3. A combination garment comprising a corset and a brassière, said brassière comprising a front portion adapted to cover the body across the busts and being attached to the 60 upper edge of the corset, end sections terminating in elastic straps, said end sections being sewn to said front portion and down the side of the corset to about the waistline and adapted to be crossed at the back, shoulder straps attached to the front portion 65

and the end sections, and means for fastening said elastic straps to the back of the corset.

4. A combination garment comprising a corset and a brassière, said brassière comprising a front portion adapted to cover the body across the busts and being sewn to the upper edge of the corset, end sections terminating in pairs of elastic straps, said end sections being sewn to said front portion and down the side of the corset to about the waistline and adapted to be crossed at the back, shoulder straps attached to the front portion and the end sections, and means for fastening said pairs of elastic straps to the back of the corset, said straps in each pair diverging from the point adapted to be fastened to the corset so that one strap of each pair is adapted to exert a pull along the lower edge of its adjacent end section and across that portion of the corset adapted to cover the diaphragm and the other strap of each pair is adapted to exert a pull along the upper edge of its adjacent end section and across the upper part of the front portion of the brassière adapted to cover the body above the busts.

5. A combination garment comprising a corset and a brassière, said brassière comprising a front portion attached to the upper edge of the corset and adapted to cover the body across the busts, end sections secured to the front portion of the brassière and down the sides of the corset to about the waistline, and means for fastening said end sections to the back of the corset, said end sections being crossed when fastened to the back of the corset.

6. A combination garment comprising a corset and a brassière, said brassière comprising a front portion attached to the upper edge of the corset and adapted to cover the body across the busts, end sections secured to the front portion of the brassière and to the sides of the corset and being free from the rear of the corset throughout the greater part of their length, and means for holding said end sections under tension across the back of the garment, said end sections extending rearwardly beyond the sides of the corset and overlapping the back of the corset, and being constructed to exert a downward pull when under tension.

7. A combination garment comprising a corset and a brassière, said brassière comprising a front portion attached to the upper edge of the corset and adapted to cover the body across the busts, end sections secured to the front portion of the brassière and to the sides of the corset and terminating in elastic straps, and means for fastening said straps to the back of the corset, said end sections being crossed where fastened to the back of the corset.

8. A combination garment comprising a corset and a brassière, said brassière comprising a front portion attached to the up-

per edge of the corset and adapted to cover the body across the busts, end sections secured to the front portion of the brassière and being free from the rear of the corset throughout the greater part of their length, 5 said end sections extending rearwardly beyond the sides of the corset and overlapping the back of the corset, and means for holding said end sections under tension across the back, said means comprising a plurality of elastic straps attached to the end of each brassière end section and constructed to exert a downward and a transverse pull on their respective brassière sections when under tension.

10 9. A combination garment comprising a corset and a brassière, said brassière comprising a front portion attached to the upper edge of the corset and adapted to cover the body across the busts, end sections secured to the front portion of the brassière and to the sides of the corset, and being free from the rear of the corset throughout the greater part of their length, 20 said end sections extending rearwardly beyond the sides of the corset and overlapping the back, and means for holding said end sections under tension across the back of the garment, said means comprising a plurality of elastic straps attached to the end of each brassière end section and constructed to exert both a downward and transverse pull on their respective brassière sections when under tension.

25 10. A combination garment comprising a corset and a brassière, said brassière comprising a front portion adapted to cover the body across the busts and being attached across the top front of the corset, end sections secured to the front portion of the brassière and overlapping the back and sides of the corset and terminating in pairs of elastic straps, 30 and means for fastening said straps to the back of the corset, said straps in each pair diverging from the point of fastening 40 to the corset so that one strap of each pair is adapted to exert a pull along the lower edge of its adjacent end section and the other strap of each pair is adapted to exert a downward pull along the upper edge of its adjacent end 45 section.

50 Signed at Chicago, in the county of Cook and State of Illinois, this 25 day of August, A. D. 1930.

KATHERINE E. CUNNINGHAM.
